UNITED STATES PATENT OFFICE.

HERBERT J. BREEZE, OF PORT HURON, MICHIGAN, ASSIGNOR OF ONE-HALF
TO HENRY P. RIEMENSCHNEIDER, OF SAME PLACE.

SAMPLE-HOLDER.

SPECIFICATION forming part of Letters Patent No. 645,047, dated March 6, 1900.

Application filed November 3, 1899. Serial No. 735,704. (No model.)

To all whom it may concern:

Be it known that I, HERBERT J. BREEZE, a citizen of the United States, residing at Port Huron, in the county of St. Clair and State of Michigan, have invented new and useful Improvements in Sample-Holders, of which the following is a specification.

My invention relates to sample-holders for dress goods and the like, and contemplates the provision of a simple and inexpensive holder susceptible of being readily placed in a bolt of goods and adapted to keep a sample smooth and otherwise in good condition and permit of it being readily drawn out as pieces are cut therefrom.

With the foregoing in mind the invention will be fully understood from the following description and claims when taken in conjunction with the annexed drawings, in which—

Figure 1 is an end elevation of a bolt of goods with my improved sample-holder in proper position therein. Fig. 2 is an enlarged perspective view illustrating the bolt of goods by broken lines and the sample-holder by full lines. Fig. 3 is a perspective view of the sample-holder, the same being shown with the sample in proper position thereon and ready to be compressed precedent to pushing it into

30 a bolt of goods.

Similar letters designate corresponding parts in all of the views, referring to which—

A is a bolt of dress goods; B, the board on which the goods is wound after the usual manner; C, a sample of the goods, and D the sample-holder.

The sample-holder may be made of any material suitable to the purpose, but in the preferred embodiment of the invention is formed in one piece of tin or other light sheet metal the edges of which are turned, as indicated by a, to prevent them from catching into and injuring the cloth of the bolt. It is made up of one or a plurality of folds b, which are formed by bending the piece of sheet metal upon itself and are adapted to receive and hold folds of the sample C after the manner best shown in Fig. 3.

The lower arm of the lowermost fold of the holder is preferably provided at its outer end with an upwardly-bent lip c, the purpose of

which is to enable the holder to more readily enter between the board B and the cloth in the bolt.

In using the holder it is expanded or permitted to expand, and the sample of cloth is placed in it after the manner shown in Fig. 3—that is to say, a fold of the sample is placed in each alternate fold of the holder and the upper end of the sample is extended slightly beyond one end of the holder. With this done the holder is compressed and is pushed into one end of the bolt A between the board B and the cloth until its outer end rests adjacent to the end of the bolt. With the parts in this position the cloth of the bolt holds the sample-holder compressed, and thereby secures the folds of the sample in the folds of the holder. As pieces are cut from the extended end of the sample by a salesman the sample is drawn out from the holder. When this is done, it will be seen that the sample will pull from one fold to another, thus keeping it remaining smooth and otherwise in good condition until entirely used up. When all of the sample has been drawn from the holder, the said holder is removed from the bolt and provided with a new sample and is then replaced in the bolt after the manner before described.

It will be readily observed that when my improved sample-holder is used in conjunction with a bolt of goods the necessity of a salesman handling the bolt when a prospective purchaser asks for a sample is obviated. It will also be appreciated that the holder is simple and inexpensive and is adapted to be readily provided with a sample and placed in and removed from a bolt of cloth without injury thereto.

Having thus described my invention, what I claim is—

1. The combination with a bolt of goods; of a sample-holder, removably arranged in the bolt and disposed lengthwise thereof; the said holder being formed of a continuous strip of material, and comprising a plurality of superposed folds, and having the bights of the alternate folds arranged at the opposite ends of the holder, and a sample having folds arranged in the folds of the holder, and an end portion arranged at the outside of the holder,

whereby the sample may be drawn from the holder as used without removing said holder from the bolt, substantially as specified.

2. As a new article of manufacture, the sample-holder described made in one piece of sheet metal and having a plurality of superposed folds, formed by bending the piece of sheet metal upon itself whereby the bights of the alternate folds are arranged at opposite

ends of the holder, and also having the lip *c* 10 at one of its ends, substantially as specified.

In testimony whereof I have hereunto set my hand in presence of two subscribing witnesses.

HERBERT J. BREEZE.
